UNITED STATES PATENT OFFICE.

RITTENHOUSE M. SMITH, OF MOBILE, ALABAMA.

FILING DEVICE.

Application filed March 27, 1920, Serial No. 369,352. Renewed July 20, 1926.

This application, which in part is a continuation of my application Serial No. 366,083, filed March 15, 1920, relates to a case or container particularly designed for use in connection with the cards of an index system, one of the objects being to provide a novel arrangement of pigeon holes or receptacles in connection with suitable designating data whereby a card can be indexed both chronologically and alphabetically or chronologically and by numbers, or alphabetically and by subject or geographical location, it being possible with this arrangement to locate a card either by the date on which the matter is to come up or by the name appearing on the card, or by the file number, or by the subject, or by geographical location, thus doing away with the two sets of cards such as have heretofore been used to enable the location of a card by means of either of the data above mentioned.

A further object is to provide the case with adjustable designating tabs by means of which one series of numerals designating the days of the month can be utilized to indicate a period of one month beginning on any day of the month.

With the foregoing and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a front elevation of a portion of the case, parts being broken away.

Figure 2 is a vertical section through the case.

Figure 3 is a section through a portion of the case on line 3—3, Figure 1.

Figure 4 is an enlarged vertical section through the top strip of the case and showing one of the tabs in position thereon.

Referring to the figures by characters of reference, 1 designates a case or housing which can be placed flat on a table or on a support or which, if preferred, can be placed

in an upright position as shown in Figure 2. This case has one face open, this face being arranged uppermost if the device is resting flat on a support and being in front if the case is upstanding. The interior of the case is divided into parallel columns by means of partitions 2 and each of these columns is, in turn, subdivided into separate pockets or pigeon holes by means of division strips 3 which are preferably inclined downwardly and rearwardly when the case is used while in an upstanding position.

It is preferred to have at least thirty-one columns and each of these thirty-one columns is preferably designated by a number, the numbers ranging from one to thirty-one in proper succession. These numbers may be suitably displayed on a strip 4 which is extended along the upper edge of the case, the upper edge of the strip being free and unobstructed throughout the length thereof and there being retaining cleats 5 along the upper and lower edge portions of the strip for holding a transparent strip 6 of glass or the like so that the numbers will thus be protected.

If more than thirty-one columns are had, the additional columns 14 and 15 and such other such columns as are had parallel to 14 and 15 except the outer column 17 may be preferably designated by names of months. For instance, at 14 would be the name of the month following the month designated by the tab "Feb." shown in the drawing and at 15 would be the name of the next succeeding month, the object being that in the pigeon holes in columns 14 and 15 would be placed cards alphabetically arranged, thus allowing an alphabetical arrangement of cards for as many months as may be desired at any one time. The cards arranged in the columns and included within the dates 1 to 31, both inclusive, would be for instance always arranged both alphabetically and chronologically, while those in columns 14 and 15 would be arranged only by the month and alphabetically, and not by days of the month.

By the use of such columns as 14 and 15 succeeding column 31, the operator could carry columns for each month of the year and thus cards could be alphabetically carried for the entire year.

Another strip 7 is arranged along one side of the case and is also preferably provided

with cleats 8 for holding a transparent strip 9, this strip extending over and protecting a series of letters arranged to constitute an index, the letter or letters opposite each 5 transverse row of pigeon holes or receptacles indicating what cards of the system should be placed in the row if properly positioned alphabetically.

Another strip 16 is arranged along the 10 center of the case from the top to the bottom of the case and is also preferably provided with cleats 19 for holding a transparent strip 12, this strip extending over and protecting a series of letters arranged to 15 constitute an index, the letter or letters opposite each transverse row of pigeon holes or receptacles indicating what cards of the system should be placed in the row if properly positioned alphabetically.

20 Another strip 17 is arranged along still another side of the case parallel to strip 16 and is also preferably provided with cleats 18 for holding a transparent strip 13, this strip extending over and protecting another 25 series of letters arranged to constitute an index, the letter or letters opposite each transverse row of pigeon holes or receptacles indicating what cards of the system should be placed in the row if properly positioned 30 alphabetically.

Across the center of the case and running at right angles to the strips containing the letters is arranged another strip provided preferably with cleats and a transparent 35 strip such as are provided at the top of the case.

The object of having more than one column containing letters and more than one column containing numbers is to place the 40 letters and numbers in close proximity to the pigeon holes throughout the case, thus enabling the eye to more readily locate a desired card or pigeon hole than would be accomplished were there only one column 45 of letters and only one column of figures, and those placed only on the outer edges of the case.

Along the bottom of the case is arranged an extra row of receptacles or pigeon holes 50 10 and under some of these are printed or otherwise displayed data indicating the months of the year. The remaining compartments or pigeon holes 10 are without any designating data and can be used for 55 any purpose desired in which event the necessary designating data can be displayed adjacent thereto. For example, these extra compartments or pigeon holes could be employed by the user for the day's work, the 60 same being divided into different hours of the day, or they can be used for different subjects, for different employees, etc.

65 Adjustably mounted on the top strip 4 are one or more tabs 11 on which are designated certain months of the year. These

tabs can be adjusted so that they will be positioned above any selected number on the strip 4.

In using the case it is intended to place a card of a certain name in the pigeon hole or compartment corresponding with a predetermined date. For example if a card in the name of Albert has reference to a matter which is to be called up on the fifth of January, said card is placed in the vertical 70 column designated by the number "5" and in the transverse row opposite the index group in which the name "Albert" belongs, this, in the present instance, being the top transverse row. Each day the January tab is moved forward to the number corresponding with the date and when this tab is brought to position above the numeral "5" on the fifth of January all the cards in the column "5" 75 will be taken out and the various matters thereon attended to. As soon as the January tab has been moved away from the number "1" the February tab can be placed thereon, so as to indicate that all the dates between the February and January tabs apply to the month of February. Thus at any 80 time after the first of January cards can be placed in pigeon holes belonging to dates in the next month provided they are within the period of one calendar month.

If it is known that there is a case to come up on any particular date but the name cannot be recalled, it will be an easy matter to locate the case by looking at the cards located under the date in question. Likewise if the name of the card is known but the date on which the case is to be brought up cannot be recalled, the card can easily be located by referring to the alphabetical index and examining all cards in the proper 105 transverse row.

Obviously by the use of this index system the operator can locate any card at any time and only one set of cards will be necessary, thus effecting a considerable saving in 110 time and material.

Should the operator on the other hand desire to do so, he might employ column 6, 16 and 17 to designate file numbers instead of to designate letters of the alphabet, as he might carry his files by numbers instead of by alphabet.

Furthermore, the operator might desire to use columns 7, 16 and 17 to designate districts or divisions of a city or other governmental sub-divisions, which could readily be done by placing the names or the designations of the divisions in columns 7, 16 and 17 in the place of the alphabet.

Furthermore, in the place of the figures in the columns indicating the days of the month the operator could carry words indicating, say subjects or articles of manufacture. For instance, in place of the Figure 1 in the top column might be placed the 125 130

word "Saws," and should the Alabama Mill Company manufacture saws, the card might be placed in the upper left hand pigeon hole, the case thus being used to 5 carry a card index of all manufacturers of, or dealers in, saws and other manufactured products

What is claimed is:

1. A card index case having parallel 10 columns of pigeon holes, each column being designated by a number corresponding with a day of a month, there being a column for each day of the month, the pigeon holes being arranged in transverse rows, and an 15 alphabetical index along one edge of the case for designating the transverse rows of pigeon holes and means adjustably associated with said day numbers for designating months.

2. A card index case having parallel 20 columns of pigeon holes each column being designated by a number corresponding with a day of the month, said pigeon holes being arranged in transverse rows, and an alphabetical index for designating the various 25 transverse rows, a supplemental row of pigeon holes, means adjacent certain of said supplemental pigeon holes for designating the month of the year, and month-designating tabs adjustably associated with said day- 30 indicating numbers.

3. A card index case having parallel 35 columns of pigeon holes, there being consecutively arranged numerals at one end of the columns for indicating the days of the month, said pigeon holes being arranged in transverse rows, an alphabetical index for designating said transverse rows of pigeon holes, tabs adjustably mounted along the day-designating numerals and indicating certain months of the year, a supplemental 40 row of pigeon holes, and means adjacent thereto for designating months of the year.

4. A card index case having parallel 45 columns of pigeon holes, each of thirty one of said columns being designated by a number corresponding with a day of the month, there being a column for each day of the month, and supplemental columns of pigeon holes parallel with the above mentioned columns and designated consecutively by the names of the 50 months of the year, the pigeon holes being arranged in transverse rows, and an alphabetical index along one edge of the case for designating the transverse rows.

5. A card index case having parallel 55 columns of pigeon holes, thirty one of said columns designated by numbers corresponding with the days of the month, there being a column for each day of the month and supplemental columns of pigeon holes parallel with the above mentioned columns and designated consecutively by the names of the 60 months of the year, the pigeon holes being arranged in transverse rows, and an alphabetical index along one edge of the case for 65

designating the transverse rows of pigeon holes, and month designating tabs adjustably mounted along the row of day-indicating numerals.

6. A card index having parallel columns 70 of pigeon holes, each of thirty one of said columns being designated by a number corresponding with a day of a month, and supplemental columns of pigeon holes parallel with the above mentioned columns and designated consecutively by the names of the months of the year, all pigeon holes being arranged in transverse rows, an alphabetical index for designating said transverse rows 75 of pigeon holes, tabs adjustably mounted along the row of day-designating numerals and indicating certain months of the year.

7. A card index having parallel columns 80 of pigeon holes, each of thirty one of said columns being designated by a number corresponding with a day of a month, there being a column for each day of the month, and supplemental columns of pigeon holes parallel with the above mentioned columns 85 and designated consecutively by the names of the months of the year, the pigeon holes being arranged in transverse rows, and an alphabetical index along each of two edges of the case and an alphabetical index extending parallel with and between said other alphabetical indices, each alphabetical index 90 designating the transverse rows of pigeon holes alike.

8. A card index having parallel columns 95 of pigeon holes, each of thirty one of said columns being designated by a number corresponding with a day of a month, there being a column for each day of the month, and supplemental columns of pigeon holes parallel with the above mentioned columns and designated consecutively by the names of the months of the year, the pigeon holes being arranged in transverse rows, and an alphabetical index along each of two edges of the case and an alphabetical index extending 100 parallel with and between said other alphabetical indices, each alphabetical index designating the transverse rows of pigeon holes alike, and month-designating tabs adjustably mounted along the row of day-indicating 105 numerals.

9. A card index having parallel columns 110 of pigeon holes, each of thirty-one of said columns being designated by a number corresponding with a day of a month, there being a column for each day of the month, and supplemental columns of pigeon holes parallel with the above mentioned columns and designated consecutively by the names of the months of the year, the pigeon holes being 115 arranged in transverse rows, and a consecutively arranged index along one edge of the case for designating the transverse rows of 120 pigeon holes.

10. A card index case having parallel col- 125

- umns of pigeon holes, thirty one of said columns being designated by different numbers corresponding with the days of the month, there being a column for each day of the 5 month, and supplemental columns of pigeon holes parallel with the above mentioned columns and designated consecutively by the names of the months of the year, the pigeon holes being arranged in transverse rows, and 10 a consecutively arranged index along one edge of the case for designating the transverse rows of pigeon holes, and month designating tabs adjustably mounted along the row of day-indicating numerals.
15. 11. A card index case having parallel columns of pigeon holes, each of thirty one of said columns being designated by a number corresponding with a day of a month, and supplemental columns of pigeon holes parallel with the above mentioned columns and designated consecutively by the names of the months of the year, all pigeon holes being arranged in transverse rows, a consecutively arranged numerical index for designating said transverse rows of pigeon holes, tabs adjustably mounted along the row of day-designating numerals and indicating certain months of the year.
12. A card index case having parallel columns of pigeon holes, each of thirty one of said columns being designated by a number corresponding with a day of a month, there being a column for each day of a month, and supplemental columns of pigeon holes parallel with said other mentioned columns and designated consecutively by the names of the months of the year, all pigeon holes being arranged in transverse rows, and a consecutively arranged numerical index along one 30 edge of the case, this index column designating the transverse rows of pigeon holes and being at right angles to the day-designating columns.
13. A card index case having parallel rows of pigeon holes, thirty one of said rows designated by different numbers corresponding with the days of the month, there being a row for each day of a month, and supplemental rows of pigeon holes parallel with said other mentioned rows and designated consecutively by the names of the months of the year, all pigeon holes being arranged in transverse rows, and a consecutively arranged numerical index along one 35 edge of the case, this index row designating the transverse rows of pigeon holes and being at right angles to the day-designating rows, and month-designating tabs adjustably mounted along the row of day-indicating numerals.
14. A card index case having parallel rows of pigeon holes, each of thirty one of said rows being designated by a number corresponding with a day of a month, and supplemental rows of pigeon holes parallel 40 with said other mentioned rows and designated consecutively by the names of the months of the year, all pigeon holes being arranged in transverse rows, an index for designating the various transverse rows, and 45 with said other mentioned rows and designated consecutively by the names of the months of the year, all pigeon holes being arranged in transverse rows, and a consecutively arranged numerical index along one edge of the case, this index designating the transverse rows of pigeon holes and being at right angles to the day-designating rows, tabs adjustably mounted along the row of day-designating numerals and indicating certain months of the year.
15. A card index case having parallel rows of pigeon holes, thirty one of said rows designated by different numbers corresponding with the days of the month, there being a row for each day of a month, and supplemental rows of pigeon holes parallel with said other mentioned rows, and designated consecutively by the names of the months of the year, all pigeon holes being arranged in transverse rows and other numerical indices designating the transverse rows of pigeon holes, such other numerical indices being in rows at right angles to the day-designating rows, and month designating tabs adjustably mounted along the row of day-indicating numerals.
16. A card index case having parallel rows of pigeon holes, there being consecutively arranged numerals at one end of the row for indicating the days of the month, there being a row for each day of a month, and supplemental rows of pigeon holes parallel with said other mentioned rows, and designated consecutively by the names of the months of the year, all pigeon holes being arranged in transverse rows, and other numerical indices designating the transverse rows of pigeon holes, such other numerical indices being in rows at right angles to the day-designating rows, tabs adjustably mounted along the row of day-designating numerals and indicating certain months of the year.
17. A card index case having parallel columns of pigeon holes, there being consecutively arranged numerals at both ends of the columns for indicating days of the month, there being a column for each day of a month, and additional supplemental rows of pigeon holes parallel with said above mentioned rows and designated consecutively by names of months of the year, all pigeon holes being arranged in transverse rows, and alphabetical indices designating the transverse rows of pigeon holes, and month designating tabs adjustably mounted along a row of day indicating numerals.
18. A card index case having parallel columns of pigeon-holes, each column being designated with a number of the day of a month, there being a column for each day of the month, said pigeon-holes being arranged in transverse rows, an index for designating the various transverse rows, and

means adjustably associated with the day indicating numbers for designating months.

19. A card index case having means for filing cards in accordance with two indexes extending at right angles to each other, one index consisting of the numbers 1 to 31, inclusive, for designating the days of the month, and the other index being alphabetical, and means adjustably associated with one of said indexes for qualifying the same.

20. A card-filing device, including in

combination, a case having an index consisting of the letters of the alphabet and a second index consisting of the numbers of the days of the month disposed at right angles to the first index, and month-designating tabs associated with the row of indicating numbers. 15

In testimony that I claim the foregoing 20 as my own, I have hereto affixed by signature.

RITTENHOUSE M. SMITH.
